UNITED STATES PATENT OFFICE.

WALTER G. SWART, FRED A. JORDAN, EDWARD W. DAVIS, AND THEODORE B. COUNSELMAN, OF DULUTH, MINNESOTA.

APPARATUS FOR MAGNETIC SIZING AND GRADING OF ORE.

1,380,871.

Specification of Letters Patent. Patented June 7, 1921.

Application filed September 11, 1917. Serial No. 190,719.

To all whom it may concern:

Be it known that we, WALTER G. SWART, FRED A. JORDAN, EDWARD W. DAVIS, and THEODORE B. COUNSELMAN, citizens of the 5 United States, residing at Duluth, in the county of St. Louis and State of Minnesota, have invented certain new and useful Improvements in Apparatus for Magnetic Sizing and Grading of Ore, of which the following is a specification.

This invention relates to improvements in apparatus for the magnetic sizing and grading of ore, and has for its object to provide apparatus for that purpose by which the 15 use of belt and bucket elevators, or similar devices, and also the use of sizing screens, may be dispensed with. In present day processes and apparatus for the magnetic separation and concentration of ores, in 20 so far as preliminary sizing and separation is concerned, bucket elevators are most generally used between the apparatus and the different stages, and screens for sizing and grading the ore as to size are utilized between the various steps. Both the bucket 25 elevators and the screens are worn out in a comparatively short time, due to the abrasive and destructive action of the broken ore, and these elements require frequent replacing, which requires considerable expense 30 not only for replacement, but for the time required therefor, and necessitates the closing down and throwing out of operation of the mills. By our apparatus we are enabled to size and grade the ore more economically 35 without screens, and in addition we may entirely reject in the first magnetic selection large tailing particles, thereby decreasing the amount of crusher capacity required in each successive stage of operation. We also magnetically separate from the other ore particles the small high grade 40 particles or fines, and these may be conducted directly to the final crushing apparatus, such as a ball mill, or the like, previous to their final concentration, thereby obviating the necessity of conveying them with the other particles through the following stages of the preliminary sizing, grading, and 45 crushing.

Another object of our invention is to provide a separating cobber, or the like, with magnets so arranged as to present a field of varying intensity through which the crushed ore particles pass, whereby it is possible to

classify the ore, as described above and as will be more fully explained hereinafter.

Still another object of our invention is to provide apparatus by which crushed ore containing magnetically susceptible material is subjected to the action of velocity and magnetic attraction, in order to enable us to separate from the high grade and valuable ore particles the large sized tailing particles and the smaller sized tailing particles, 60 and thus enable us to dispose of these two sizes as a by-product for use as railroad ballast and road-building material, as well as obviating the necessity for further screening and sizing before disposing of said tailings. 65

In the accompanying drawings—

Figure 1 is a perspective view of one cobber set.

Fig. 2 is a side elevation of the same. 75

Fig. 3 is a diagrammatic view of a wiring arrangement to permit variation of the intensity of the magnets of one cobber.

Fig. 4 is a diagrammatic flow sheet, showing one arrangement of multi-stage apparatus. 80

Fig. 5 is a similar view of a different arrangement; and

Fig. 6 is a similar view of still another arrangement. 85

Like numerals refer to like elements throughout the drawings.

In Fig. 1 is shown a perspective view of one cobber set, the showing being partially diagrammatic for clearness. 10 designates 90 a pulley or drum rotating with a hollow shaft 11, which rotates upon the hollow sleeve or shaft 14. 12 designates a driving belt operating the pulley 10. A belt conveyor 17, preferably of resilient material, such as rubber, to resist the abrasive action of the ore particles, passes around the pulley 13 and around the cobber drum 15, which is driven by the hollow shaft 11 and rotates upon the hollow sleeve 14. 18 is a chute leading from the preliminary crushing rolls and delivering the ore as it is first crushed from the rollers—see Fig. 4, for example—upon the belt 17, by which it is conveyed to the cobber drum, as shown in Fig. 1. 100 Partitions A, B are shown in Figs. 1 and 2 as providing deposit bins or spaces X, Y, and Z, respectively, as will be more fully described later. Stationary magnets, generally indicated by numeral 20 and specifi- 105

110

cally indicated by the letters *a*, *b*, *c*, *d*, *e*, *f*, and *g*, are provided, as shown in Fig. 3, the same being connected by the magnet yoke 20' carried upon the hollow sleeve 16. The main branch or feed wires 21, 22 are provided, and excitation current wires surround each of the magnets 20 and are located in parallel between the feed wires 21 and 22. In Fig. 3 we have shown a rheostat 24 as being provided in each of the magnet circuits for the purpose of varying the current flow through the coils 23 and permitting individual regulation of the intensity of each magnet. It will be obvious that any number of magnets of any desired excitation may be provided without departing from the spirit of the invention.

In Fig. 3 we have shown magnets *a*, *b*, and *f*, *g* as being more strongly excited than the intermediate magnets, for a purpose hereinafter to be described.

In Fig. 4 is illustrated a multi-stage apparatus in diagrammatic form, in which crushing rolls 7 receive the ore by the chute 6, through the medium of the conveyer 5, from the bin or the like—not shown. As stated above, after crushing by the rolls 7, the crushed particles of the desired size, for example, two inch mesh, are deposited upon the resilient belt 17 and carried to the first cobber 15, by which a two-part separation is effected in contradistinction to the three-part separation described in connection with Figs. 1 to 3. This is a comparatively crude or imperfect form of separation, and consists in separating the ore particles into small high grade particles or fines, which are carried into the collection bin, or the like, 31' for removal to the final crushing stage in a ball mill, thereby obviating the necessity of their further treatment by this preliminary apparatus. All the other particles are deposited by the shed 31 upon the conveyer belt 170, for conveyance to the second cobber drum 150, which also effects a two-part separation, whereby large tailing particles of low magnetic susceptibility are carried by the shed 32 to a collection receptacle 32', thus dispensing with their further crushing and treatment by this apparatus, and thereby increasing its capacity in the further stages of operation. All other particles are carried by the cobber drum 150 and shed 32 to a second set of crushing rolls 70, which deposits them as crushed to a smaller size upon the second conveyer belt 170, by which they are conveyed to a third cobber 151, similar to the cobber 15, and a two-part separation is again effected, as described above. Subsequent operations similar to those first described are carried on according to the nature and necessary treatment of the ore until the final preliminary stage, where the last cobber drum 155 finally separates the ore particles, depositing the tail-

ings upon the conveyer *x*, or the like, and the final fines upon the conveyer *y* for removal to the ball mill—not shown.

In Fig. 5 is shown another flow sheet embodying a slightly modified form of apparatus which utilizes the conveyer 5, chute 6, preliminary crushing rolls 7, chute 18, and first cobber 15, as in the apparatus of Fig. 4. The cobber 15, however, in the form shown in Fig. 5 is operated to effect a three-part separation, as in the structure of Figs. 1 to 3, save that while the fines are collected in the bin 50 and the middlings carried by shed 51 to the second set of rolls 70, the large tailing particles are deposited by shed 52 upon the conveyer belt 170 for a second treatment by cobber 150, which separates the large tailings into two parts, one of which consists of the particles of low magnetic susceptibility. These particles are deposited by shed 150' in the collection bin or space 32', while the large tailing particles, considered of sufficient metal content to render their further treatment desirable, are carried by the shed 150 to the rolls 70 with the middlings. Subsequent stages utilize the same apparatus as that first described to perform subsequent similar operations, the retained middlings in each instance being crushed smaller and smaller until the final separation takes place by means of cobber 155.

In Fig. 6 is shown still another form or arrangement of apparatus in which a single cobber drum is utilized in each stage of operation after crushing of the ore by preliminary crushing rolls 7, and its deposit by chute 18 upon the conveyer belt 17 for conveyance to the first cobber drum 15, which, as in the showing of Figs. 1 to 3, effects a three-part separation, the fines and small particles being deposited in bin *Z*, the large tailings being deposited in bin *X*, and the middlings and all particles of varying metal content being carried by the partitions *A*, *B* to the second set of crushing rolls 70. These operations are repeated as many times as are desirable until final separation by the last cobber drum 155, as in the other forms described.

In the use and operation of this apparatus, the forces acting upon the ore particles—after they are crushed and deposited upon the conveyer belt 17—are the momentum or velocity imparted to them by the movement of the belt in their travel toward the cobber drum 15; the magnetic attraction exerted upon them varying according to the intensity of the magnetic field and substantially inversely according to the square of the distance of the center of magnetic attraction of each particle from the source of magnetic power, *i. e.* magnetic poles; and the force of gravity. In the travel of the particles to the cobber drum, were the magnets not excited

the particles, save as affected by the resistance to their movement by the air through which they pass, would be projected outwardly in a path approximating a parabola. The large particles are naturally less affected by the resistance of the air and travel farther from the copper drum than would the smaller particles, and more closely approximate this parabolic trajectory. With the magnets in operation the large particles of low magnetic susceptibility subjected to attraction by the magnets would be affected to little or no extent by the magnetic attraction, and are projected a substantially greater distance from the copper than the particles containing iron ore, for example—such as magnetite. Large particles of low or middling grade, as stated, will be attracted to the copper drum by the magnets according to the distance of their magnetic center of attraction from the magnet poles. In fact, all particles having any magnetic susceptibility will be so affected, and the small high grade particles, being in comparatively close proximity to the source of magnetic attraction, will be retained in close contact with the copper drum and, by proper regulation of the magnet intensity, the middling particles, especially those of comparatively large size, will be carried through a lesser arc of travel by the copper drum, owing to the action of the momentum, the force of gravity, and the comparatively weak attraction exerted upon them, while the small high grade particles or fines will be carried through a greater arc of travel, and advantage is taken of this fact to effect the three part separation above described. This effect may be enhanced by the proper regulation of the magnetic intensity, as shown in Fig. 3, for example. The rheostats controlling the current flow around the different magnets and are so arranged as to present a comparatively strong magnetic attraction of the magnets *a*, *b*, which first exert attraction upon the ore particles as they are conveyed to the copper. This relatively strong attraction will not affect the large low grade and tailing particles of low magnetic susceptibility, which will be thrown outwardly as described above. It may, however, be of sufficient strength to cause the middling particles, especially those of large size, to be held by the copper drum until the large tailing particles have been rejected, and when in the course of its travel the excitation of the less excited magnets *c*, *d*, and *e* is encountered the force of gravity and the momentum is sufficient to counteract the attraction of the magnets upon these larger middling particles, and they will accordingly drop in the bin *B*, as described. This weaker excitation, however, will be sufficient to retain the fines and particles of great magnetic susceptibility upon the copper drum, although the excitation may be so controlled as to permit large particles of relatively great magnetic susceptibility to pass with the middlings as requiring further crushing. As the magnets *f* and *g* exert their attraction upon the particles which still cling to the copper drum, they will retain the fines and particles of great magnetic susceptibility until the middlings and large retained particles have all been rejected or allowed to drop, so that the fines may be readily separated and deposited in the bin *Z* as they pass beyond the attraction of the magnets. This three-part separation permits the early and preliminary rejection of the large tailing particles, as stated above, which does away with the necessity for further treatment and crushing by this apparatus, thereby considerably increasing the capacity of the apparatus, by eliminating the material which it is unnecessary further to treat and crush. The same is true of the fines or high grade concentrates which may be taken directly to the final crushing element, such as a ball mill, previous to the final concentration.

By utilizing our apparatus in an initial stage, separating the large tailing particles from the remainder of the crushed ore, we obtain relatively large tailing particles capable of use as railroad ballast, while the smaller tailing particles are carried into the bin or space with middlings and larger high grade particles. A second stage of treatment in a similar manner will result in the reduction of these tailings of smaller size, the same being adaptable for use and sale as road-building material, this two-stage reduction of the tailings resulting in a definite grading or sizing of the particles without the use of screens or other sizing elements prior to their sale or use.

It will be obvious that our apparatus is susceptible of modifications and improvements, and that variation in number and kind of magnets may be made as desired and necessitated by the kind of ore treated; also the method of varying the excitation of the arrangement of the differently excited magnets may be varied—all without departing from the scope or spirit of our invention as defined in the appended claims.

What we claim is:—

1. In apparatus of the class described a rotatable drum and a series of electro-magnets distributed in arcuate form within and adjacent the periphery of said drum and co-acting therewith to attract magnetically susceptible particles carried thereto some of said magnets being of relatively strong excitation and other magnets being of relatively weak excitation to produce substantially distinct areas of variable magnetic potency and means for changing the location of said areas.

2. In apparatus of the class described a rotatable drum a series of electro-magnets distributed in arcuate form within and adjacent the periphery of said drum and co-acting therewith to attract magnetically susceptible particles carried thereto and means to vary the strength of the exciting current of said magnets independently of each other as desired. 30
- 10 3. In apparatus of the class described, a drum, a belt running on said drum to convey ore particles thereto, a plurality of magnets located within said drum, said magnets being regulable as to attraction, to magnetically attract middling ore particles and large high grade ore particles to cause them to deviate from their normal path and to further attract and separate the fine ore concentrates from said middling and high grade ore particles. 35
- 15 4. In apparatus of the class described, a drum, magnets located within and adjacent the periphery of said drum, means to deliver ore particles over said drum with predetermined velocity said magnets being separately and independently regulable as to 40
- 20
- 25

magnetic strength to withdraw all save the tailing particles from the path of the latter and to thereafter withdraw the fine concentrates from the remainder. 30

5. In apparatus of the class described, a drum, means to deliver ore particles to said drum, a plurality of magnets located within said drum, all of said magnets being operative to attract magnetizable particles, certain of said magnets being of relatively great excitation, others of said magnets following said magnets of greater excitation being of weaker excitation, and certain other of said magnets following said magnets of weaker excitation being of relatively greater excitation. 40

In testimony whereof, we have subscribed our names.
